J. KARCEVSK

ELECTRIC HAMMER

Filed April 25, 1927

Inventor
John Karcevsk
by *Chattwood & Son Atty.*

UNITED STATES PATENT OFFICE.

JOHN KARCEVSK, OF CHICAGO, ILLINOIS.

ELECTRIC HAMMER.

Application filed April 25, 1927. Serial No. 186,351.

This invention relates to improvements in electric hammers and it consists of the matters hereinafter described and more particularly pointed out in the appended claims.

The improved hammer is of the motor driven type and includes a reciprocating member receiving its power stroke from a spring and its return or lifting stroke through the action of a motor driven cam shaft.

One of the objects of the present invention is to provide a hammer of this kind wherein the reciprocating member may be temporarily disconnected from the motor driven shaft whereby the motor is relieved from a load during the starting thereof, and which member may be operatively connected to said shaft, after the motor is in operation.

A further object of the invention is to provide in connection with the driving motor, a fly or balance wheel which improves the operation of the motor and permits the use of a smaller motor and a small over all dimension for the hammer as a whole.

Still another object of the invention is to provide a hammer of this kind wherein the weight is more evenly distributed and a better balance provided therefor which relieves the operator from a considerable strain while using the hammer.

A still further object of the invention is to provide a hammer of this kind which though light in weight is powerful in operation and is capable of striking harder and more effective blows which is desirable in drilling in concrete and the like.

These objects of the invention, as well as others, together with the many advantages thereof, will more fully appear as I proceed with my specification.

In the drawings:

Fig. 1 is a longitudinal sectional view through an electric hammer embodying the preferred form of my invention.

Fig. 2 is a view in front elevation of the same, with the front plate thereof shown as removed to more clearly disclose the interior construction thereof.

Fig. 3 is a detail sectional view through the several parts of the casing and motor as taken on the line 3-3 of Fig. 2.

Fig. 4 is a detail view in side elevation of a part of the hammer and which will be more fully referred to later.

Referring now in detail to that embodiment of the invention illustrated in the accom-

panying drawing, 1 indicates as a whole the casing for my improved hammer which includes an annular head 2 and a radially disposed tubular extension or barrel 3. The head 2 is defined by an annular flange 4 divided intermediate its ends by a partition or wall 5, thus leaving said head open at its front and rear. In said annular flange 4 in front of the wall 5 is an opening 6 communicating with the interior of the barrel 3. Coaxially with the wall 5 is a rearwardly extending bearing boss 7 the purpose of which will later appear and on the flange 4 directly opposite the tubular extension 3 is a closed grip handle 8 to be grasped in manipulating the hammer. The open front end of the annular head is closed by a front plate 9, while the open rear end of said head is closed by the casing of an electric motor 10. I find one convenient way to hold said parts together is to provide bolts 11-11 which extend through the motor casing from the rear and which pass through bosses 12-12 on the flange 4 to be screwed into the front plate all as best shown in Fig. 3. The front plate 9 is provided with a bearing boss 13 in line with the like boss 7 before mentioned. 14 indicates the armature shaft of the motor 10 which shaft has bearing in the sleeve 7. The forward end of this shaft is reduced in diameter as at 14^a and on said end part of reduced diameter is a sleeve 15 carrying a cam 16. Said sleeve 15 is journalled in the boss 13 of the front plate and mounted on said sleeve outside of the front plate is the hub of a balance wheel 17, a pin 17^a passing through said hub, sleeve and shaft part 14^a of reduced diameter.

The balance wheel 17 is of a diameter approximating that of the casing head and its action permits the use of a smaller size motor. While the shaft 14 in this instance has been described as the armature shaft, this is to be considered as by way of illustration only because it may be a shaft other than an armature shaft and still be driven by it through suitable gearing or the like. The construction just described provides a good bearing for the shaft 14 and reduces the axial dimensions of the head of the hammer and permits a quick disassembly for inspection and cleaning.

On the front face of the wall 5 is provided spaced guide plates or ways 18 in which the cross head 19 of a reciprocating member 20

has sliding guiding bearing. In said cross head is provided a longitudinal slot 21 to accommodate the shaft 14. On the cross head just above the slot 21 is journaled a roller 22 adapted in the rotation of the shaft 14 to be engaged by the cam 16 to impart the return or lifting stroke to the reciprocating member. The cross head has a top extension 23 which includes a forwardly extending stud 10 or pin 24. The reciprocating member 20 extends through the opening 6 into the tubular barrel 3 where it is suitably fixed to a hammer head or impact member 25 which has sliding guiding bearing in the tubular barrel 3. In said head are provided two longitudinal openings 25^a through which air in advance of the hammer may escape from the barrel. A helical expansion spring 26 surrounds the reciprocating member 20, 20 between the impact member or hammer 25 and that part of the flange 4 defining the opening 6. On the return or lifting stroke of the reciprocating member 20 under the action of the cam on the shaft 14, the spring 25 is compressed and placed under tension and so soon as the cam sweeps past the roller 22, the spring acts to impose the power stroke on said reciprocating member.

In the open end of the tubular extension 30 or barrel 3 is threaded a tubular plug 27, the extreme free end of which is made hexagonal as shown in Fig. 2 for the application of a wrench. Said plug has an axially disposed bore 27^a in which the shank 28 of 35 the tool 29 has bearing, said shank projecting a sufficient distance beyond the inner end of said plug to be engaged by the impact member 25. On said tool below or beyond the plug 27 is formed an annular 40 shoulder 30 to be engaged by a part of a tool retainer 31, the same including laterally spaced yielding arms 32 each pivoted at its free end to the barrel as at 33. This connection of said arms permits the retainer to 45 be swung away from the shoulder 30 when so desired, for the easy removal and replacement of the tool.

Means are provided to remove the reciprocating member from the influence of the 50 cam on the shaft 14 so that the motor may be started without the load or resistance of said member, after which said member may be brought into position with respect to the cam so that it may operate for its intended 55 purpose. I have found one convenient and simple means for such purpose to be as follows: On the rear or inner face of the cover plate 9 I pivot as at 35, a cam 36 which includes a lever 37 extending outwardly through a suitable slot 38 in the casting flange 4. At each end of the slot is provided a shoulder 39—39^a behind which the lever may be engaged to hold it in one or the other of its positions, as best shown in 60 Fig. 4. Said cam 36 is so formed that when

it is swung toward the grip handle 8 it will engage the stud 24 and will move the reciprocating member so that the roller stud 22 is not engageable by the cam 16. This permits the easy starting of the motor without load, a switch trigger 40 in the handle controlling the supply of current by the motor. When the lever 37 is swung clockwise as in Fig. 2 to engage behind the other shoulder 39^a the stud is released from the influence of the cam 36 so that the roller stud 22 may again be acted upon by the cam 16 on the shaft 14 to impart the return movement to the reciprocating member as before described after the motor is in operation.

My improved hammer is light and balanced in weight and is capable of striking a powerful blow. It is simple in construction and the parts are easily assembled.

While in describing my invention I have referred in detail to certain forms and arrangement of the parts thereof, I do not wish to be limited thereto except as may be pointed out in the appended claims.

I claim as my invention:

1. An electric hammer of the kind described embodying therein a casing having an annular head and a barrel extension, said head being open at its front and rear end and having a middle partition wall, a motor closing the rear of the casing, a front plate closing the front of the casing, means securing said motor, head and front plate together, a shaft journaled in said wall and 95 plate and driven by the motor, a reciprocating member in said barrel extension, means connecting said shaft and reciprocating member for imparting a movement thereto in one direction, and a balance wheel fixed 100 to said shaft adjacent the front plate.

2. An electric hammer embodying therein a casing, a reciprocating impact member having a sliding guiding bearing therein, a shaft and a motor for driving the same, 110 means on said shaft for imparting a movement in one direction to said reciprocating member and means adapted to be engaged with a part of said reciprocating member for removing it from the influence of said 115 first mentioned means.

3. An electric hammer of the kind described embodying therein a casing having an annular head and a barrel extension, said head being open at its front and rear and having a middle partition, a motor closing one end of the casing and a plate closing the other end of the casing, a shaft journaled in said partition and plate and driven by the motor, a reciprocating member with a part 120 arranged in the barrel, guide plates on said partition in which said reciprocating member has sliding bearing, coacting means on said shaft and member for reciprocating it in one direction and means adapted to be 125 130

engaged with a part of said reciprocating member for removing it from the influence of said coacting means.

4. An electric hammer of the kind described embodying therein a casing having an annular head and a barrel extension, said head being open at its front and rear and having a middle partition, a motor closing one end of the casing and a plate closing the other end of the casing, a shaft journalled in said partition and plate and driven by the motor, a reciprocating member with a part arranged in the barrel, means on said partition providing guiding bearing for said reciprocating member, coacting means on said shaft and member for reciprocating said member in one direction, a stud on said reciprocating member and a lever cam pivoted on said front plate and adapted to be engaged with said stud to remove said member from the influence of said coacting means.

10 15 20 25

5. An electric hammer of the kind described embodying therein a casing having an annular head and a barrel extension, said head being open at its front and rear end, a motor closing one end of the casing and including an armature shaft, a plate closing the other end of the casing, and in which said shaft is journalled, removable means for securing said motor, plate and casing head together, a reciprocating member in said barrel extension, means connecting said armature shaft and reciprocating member for imparting a movement thereto in one direction and a balance wheel fixed to said shaft adjacent said front plate.

in said partition and plate and driven by the 30 motor, a reciprocating member with a part arranged in the barrel, means on said partition providing guiding bearing for said reciprocating member, coacting means on said shaft and member for reciprocating said 35 member in one direction, a stud on said reciprocating member and a lever cam pivoted on said front plate and adapted to be engaged with said stud to remove said member from the influence of said coacting means.

6. An electric hammer of the kind described embodying therein a casing having an annular head and a barrel extension, said head being open at its front and rear end, a motor closing one end of the casing and including an armature shaft, a plate closing the other end of the casing, and in which said shaft is journalled, removable means for securing said motor, plate and casing head together, a reciprocating member in said barrel extension, means connecting said armature shaft and reciprocating member for imparting a movement thereto in one direction and a balance wheel fixed to said shaft adjacent said front plate.

40 45 50 55

In testimony whereof, I have hereunto set my hand, this 21st day of April, 1927.

JOHN KARCEVSK.
